UNITED STATES PATENT OFFICE.

GEORGE W. CURTIS, OF NEW BRITAIN, CONNECTICUT.

SHELF.

No. 883,001.

Specification of Letters Patent. Patented March 24, 1908.

Application filed May 28, 1907. Serial No. 376,050.

To all whom it may concern:

Be it known that I, GEORGE W. CURTIS, a citizen of the United States, and a resident of New Britain, in the county of Hartford and 5 State of Connecticut, have invented a new and Improved Shelf, of which the following is a full, clear, and exact description.

This invention relates to shelves, and more particularly to that class of shelves adapted 10 to be secured at window frames to carry potted plants and the like.

The object of the invention is to provide a simple, strong and durable shelf, which can be removably mounted at the frame of a 15 window and which is adapted to fit windows of different sizes.

A further object of the invention is to provide a shelf comprising carrying members adapted to be removably attached to window frames and the like without material injury thereto, and extensible shelves or pans removably arranged upon said carrying members.

The invention consists in the construction 25 and combination of parts to be more particularly described hereinafter and fully set forth in the claims.

Reference is to be had to the accompanying drawings forming a part of this specification, in which similar characters of reference indicate corresponding parts in all the views, and in which

Figure 1 is a perspective view of a window showing my invention secured to the frame 35 thereof; Fig. 2 is a longitudinal cross-section of the shelf; Fig. 3 is a side elevation of a carrying member; and Fig. 4 is a cross-section of a detail on the line 4—4 of Fig. 3.

Before proceeding to a more detailed explanation of my invention, it should be understood that my shelf is particularly useful for supporting growing plants near windows to permit the plants to receive the necessary light and air. Often the plants 45 are merely placed upon the lower part of the window casing, where they are in the way when it is necessary to open or close the windows, and where they are liable to be injured in this operation by being displaced from the 50 window casing. My shelf may be secured to the window frame at any point intermediate the height of the same, and will fit any window of ordinary size, as the shelf is extensible. The carrying members for supporting 55 the shelf proper may be secured to the window frame at substantially any point thereof,

or may be secured to the wall adjacent to the window. The attaching parts of the carrying members are provided with surfaces of material such as rubber, where they engage 60 the support, so that injury to the latter is obviated.

Referring more particularly to the drawings, 1 represents the frame of a window 2 of the usual construction. At the inner edges 65 of the window, side members of the window frame are provided with projecting screws or nails 3 for securing the carrying members in position. The shelf brackets comprise angle members 4, the outer faces of the flanges of 70 which are provided with surfaces 5 of rubber, felt or other similar material secured in position by gluing or in any other manner adapted to the purpose. Near the extremities the flanges of the angle members are provided 75 with elongated slots 6 having extended portions 7 near the center. The attaching members can be secured to the window frame by means of the screws or nails 3 which are arranged in the slots 6, the heads of the 80 screws or nails passing through the enlarged portion 7 of the slots, while the shanks of the former engage the upper ends of the slots 6 when the attaching members are in position. The heads of the screws or nails prevent the 85 displacement of the angle members therefrom, unless the latter are manipulated to permit the heads to pass through the enlarged portions 7 of the slots. It will be 90 understood that by using angles for the attaching members it is possible to arrange the brackets at angles of the window frame or upon the wall adjacent to the frame, or in fact upon any support offering a flat surface 95 against which the face of one flange of the angle can abut.

The bracket has a supporting member 8 consisting preferably of a bar bent upon itself to form a U and having substantially parallel parts or members 9; the ends 10 of 100 the bar are flattened and are secured to a flange of the supporting angle by means of suitable rivets 11. The shelf *per se* comprises relatively slidable pans 12 and 13. The pan 12 has sides, a bottom and an end, being 105 open at the opposite end. The edges of the sides are formed into laterally disposed tubular flanges 14 adapted to telescope within the similarly formed tubular flanges 15 of the pan 13, which also has a bottom, sides and 110 an end. The tubular flanges 15 are of course of suitable diameter to receive the

smaller flanges 14. At opposite ends, the pans 12 and 13 respectively have bracket plates 16 secured to the end plates by soldering or riveting and presenting at the upper edges outwardly grooved flanges 17 adapted to engage the carrying member to support the shelf. The attaching flange 17 may be mounted upon the upper or lower of the parallel carrying members and holds the shelf 10 removably thereupon.

It will be understood that as the shelf is extensible it can be arranged to fit a window of any size, within ordinary limits. The brackets of my shelf are reversible, and can 15 thus be used either side up. This feature obviates the necessity of having the brackets in suitable pairs, as any bracket of my invention can be used together with any other similar bracket.

20 Having thus described my invention, I claim as new and desire to secure by Letters Patent:—

1. In a device of the class described, a bracket comprising an angle member having 25 flanges, one of said flanges having an opening formed to receive and operatively engage a supporting projection, and a supporting member comprising a U-shaped bar having the ends rigidly mounted at a flange of said 30 angle member.

2. In a device of the class described, a bracket comprising an angle member having flanges presenting protective outer faces, 35 said flanges having elongated openings presenting enlarged portions to receive support-

ing projections, and a supporting member comprising a U-shaped bar having the ends rigidly mounted at a flange of said angle member.

3. In a device of the class described, a 40 bracket comprising an angle member having flanges, one of said flanges having an opening arranged to receive and operatively engage a supporting projection, a supporting member comprising a U-shaped bar having the 45 ends rigidly mounted at a flange of said angle member, and an extensible shelf comprising telescoping pans, one of said pans having at the end a supporting flange adapted to be removably carried by said bar. 50

4. In a device of the class described, brackets comprising angle members having flanges presenting protective outer faces, said flanges having elongated openings presenting enlarged portions to receive supporting projections, said brackets having supporting members comprising U-shaped bars having the ends rigidly mounted at flanges of said angle members, and an extensible shelf comprising telescoping pans 60 having at the ends supporting flanges adapted to be removably carried by bars of said supporting members.

In testimony whereof I have signed my name to this specification in the presence of 65 two subscribing witnesses.

GEORGE W. CURTIS.
